UNITED STATES PATENT OFFICE.

CLAUDE W. KRESS, OF NEW YORK, N. Y.

DISPLAY FIXTURE.

Application filed January 16, 1926. Serial No. 81,857.

The present invention is concerned with improvements in display fixtures, particularly with the type of fixture which is employed for supporting a portable divider or partition in vertical position upon a display counter.

In the display of merchandise upon counters, it is frequently desirable to subdivide the counter into a plurality of shallow compartments by the use of partition or divider members, the latter in many instances being of sheet glass. The sheet glass stock always varies considerably in thickness, and no satisfactory fixture has heretofore been provided for securely and effectively supporting such glass partitions.

It is a specific object of the present invention to provide a display fixture in the nature of a divider support, which will be self-accommodating to compensate for the variations in the thickness of the glass partitions, and which will at all times hold the glass against rattling or vibration and against accidental tipping over.

Other objects of the invention are to provide a display fixture of this character which will be of simple, practical construction, which will be rugged and durable in use, neat and attractive in appearance, and well suited to the requirements of economical manufacture.

With the above noted and other objects in view, the invention consists in certain novel features of construction and combinations and arrangements of parts, as will be more fully hereinafter set forth and pointed out in the claim. The invention may be more fully understood from the following description in connection with the accompanying drawings, wherein

Fig. 1 is a perspective view showing a partition member supported by one of my improved display fixtures.

Fig. 2 is a fragmentary view in elevation, showing a partition member operative supported by the fixture.

Fig. 3 is a top plan view of Fig. 2.

Fig. 4 is a side elevational view of one of the fixtures with the partition removed.

In the drawings I have used the reference character 10 to designate a counter or other suitable supporting surface upon which merchandise is adapted to be disposed for display purposes. The conventional type of divider or partition is illustrated at

11, this partition in the present instance being of sheet glass.

My improved display fixture, which is adapted for supporting this partition in vertical position on the counter is designated generally by the reference character 12. It is preferably formed of a pair of approximately L-shaped metallic members 13 riveted or otherwise secured at 14 to a base bar 15. The bar 15 and the angle members 13 are formed of any suitable material such for instance as brass, and are preferably of similar gauge and width. The longer arms 16 of the L-shaped members 13 overlie the face of the base bar 15, and are secured thereto by the rivets. The shorter arms 17 of the L-shaped members 13 rise vertically adjacent the center of the fixture and are adapted to straddle the lower edge of the partition 11 preferably at a point near one end of the partition.

In order that the fixture may tightly engage the partition regardless of the thickness of the latter, I provide a spring clamping element 18, one end 19 of which is clamped between the longer arms 16 of one of the L-shaped members 13, and the base bar 15. The spring member 18 is in the nature of a flat strip of spring metal, and the free end 20 thereof defines a spring finger rising between the posts 17, and normally bearing by its inherent resiliency against one of the posts, as seen in Fig. 4. It will be noted that the free end of the spring finger 20 projects above the posts as indicated at 21 in order to facilitate the application of the fixture to the partition 11.

When applying the fixture to the partition, the partition is laid on its side with the edge projecting over the table, and the free end 21 of the spring finger is engaged with such projecting edge. Downward pressure on the fixture will cause the finger 20 to be retracted and permit the fixture to be slipped over the edge of the glass with the finger bearing against the glass, as seen in Fig. 2. The partition is thus firmly held against rattling or vibration, and the spring finger is self-accommodating to tightly clamp various gauge partition plates.

It will be obvious that the fixture may be used for supporting partitions other than glass partitions, and that numerous changes and alterations might be made in the gen-

2
eral form and arrangement of parts de-
scribed without departing from the inven-
tion. Hence I do not wish to limit myself
to the details set forth, but shall consider
5 myself at liberty to make such changes and
alterations as fairly fall within the spirit
and scope of the appended claim.

I claim:

10 A display fixture for supporting plate
glass counter dividers, including a base bar,
a pair of L-shaped members each having a
horizontal leg overlying and secured to the

bar, the other legs of the L-shaped members
projecting upwardly and adapted to strad-
dle a divider, and spring clamping means 15
associated with said last mentioned legs,
said clamping means including a flat strip
of spring metal, one end of which is clamped
between the base bar and the horizontal leg
of one L-shaped member, and the other end 20
of which extends upwardly between the
vertical legs of the L-shaped members.
